UNITED STATES PATENT OFFICE.

CHARLES LISS, OF NEW YORK, N. Y.

OVERFLOW-ALARM.

SPECIFICATION forming part of Letters Patent No. 620,713, dated March 7, 1899.

Application filed December 28, 1898. Serial No. 700,485. (No model.)

To all whom it may concern:

Be it known that I, CHARLES LISS, a citizen of Germany, and a resident of New York, (Brooklyn,) county of Kings, and State of New York, have invented new and useful Improvements in Overflow-Alarms, of which the following is a specification.

This invention relates to an electric overflow-alarm for refrigerators and similar articles in which the alarm-box is removably attached to the drip-pan by means of a frame of peculiar construction, which also constitutes a support for the actuating-lever that sets the alarm off.

15 In the accompanying drawings, Figure 1 is a vertical section of my improved overflow-alarm on line 1 1, Fig. 2. Fig. 2 is a plan thereof, and Fig. 3 a detail perspective view of the frame *a*.

20 The letter *a* represents a frame adapted to straddle the wall of the drip-pan *A* of a refrigerator, &c., and to removably support an alarm-box *B* of conventional construction.

The frame *a*, as illustrated in Fig. 3, is 25 composed of a continuous bar or wire, the shanks of which extend downward, as at *a'*, and then upward, as at *a*². Thus upper hooks *a*³ are formed that are adapted to engage the pan *A*, while the lower hooks *a*² grasp one of the sides of the box *B*, and thus hold such 30 box tightly against one side of the pan, Fig. 1.

The box *B* is provided with a dry battery *b*, electromagnets, (in case *b'*,) gong *b*², clapper *b*³, spring-contacts *b*⁴ *b*⁴, and the circuit-wires, which when contact is established close 35 the circuit to set off the alarm.

Above the upper bend *a*³ of frame *a* are 40 formed a pair of bearings *a*⁴, in which turns a longitudinal shaft *c*. To this shaft there is affixed a lever *c'*, having its shorter downwardly-bent arm *c*² placed vertically above and between the contacts *b*⁴. This arm is guided in its vertical movement by a U-shaped

guard *e*, projecting upwardly from box *B*. The longer lever-arm projects partially across 45 pan *A* and carries a suitable float *d* by means of a suspending-rod *d'*.

In use the frame *a* is set to straddle the pan *A*, and then the box *B* is hooked into the frame, so that in this way the parts are assembled in a simple manner. The drip-water upon accumulating will gradually raise the float, which will in turn swing the lever *c'*. When the danger-point has been reached by the drip-water, the lever-arm *c*² will enter 55 between and connect the two contacts *b*⁴ to close the circuit and sound the alarm. When the water has been poured out, the float will fall to raise the lever-arm *c*², break the contact, 60 and stop the alarm.

It will be seen that by my invention an alarm-box may be operatively secured to overflow-basins in a simple and reliable manner and without requiring any fitting or skilled 65 adjustment.

What I claim is—

1. A frame for overflow-alarms having an upper hook adapted to straddle the drip-pan, and a lower hook adapted to engage the alarm-box, combined with a shaft hung in the frame, 70 a contact-lever supported upon the shaft, and a float suspended from the lever, substantially as specified.

2. An overflow-alarm composed of a frame having upper and lower hooks, a shaft hung in the frame, a lever supported upon the shaft, a float suspended from the lever, and an alarm-box adapted to be engaged by the lower hook and provided with an electric bell, circuit-wires, a pair of contacts, and a guide adapted 80 to embrace the lever, substantially as specified.

CHARLES LISS.
